(57) **CLAIM**

The ornamental design for a golf putter head, as shown and described.

DESCRIPTION

FIG. 1 is a perspective view of a golf putter head embodying the new design.

FIG. 2 is a rear and left side perspective view of the golf putter head shown in FIG. 1.

FIG. 3 is an inverted front and bottom perspective view of the golf putter head shown in FIG. 1.

FIG. 4 is a back elevation view of the golf putter head shown in FIG. 1.

FIG. 5 is a front elevation view of the golf putter head shown in FIG. 1.

FIG. 6 is a left side elevation view of the golf putter head shown in FIG. 1.

FIG. 7 is a right-side elevation view of the golf putter head shown in FIG. 1.

FIG. 8 is a top plan view of the golf putter head shown in FIG. 1; and,

FIG. 9 is a bottom plan view of the golf putter head shown in FIG. 1.

The broken line showing the putter shaft fragment, the face grooves, and the alignment grooves in the rear pocket form no part of the claimed design.

1 Claim, 6 Drawing Sheets
